CLAIM

(21) Appl. No.: **29/151,648**

The ornamental design for an icon or label for display on cartridges for office equipment or electronic displays, as shown and described.

(22) Filed: **Nov. 13, 2001**

DESCRIPTION

(51) LOC (7) Cl. **14-02**

FIG. 1 is a front view of an icon or label for display on cartridges for office equipment or electronic displays; FIG. 2 is a front view of a second embodiment thereof; and, FIG. 3 is a front view of a third embodiment thereof.

(52) U.S. Cl. **D14/489**

The broken line drawings of a portion of cartridge or electronic display in FIG. 1, the electronic display in FIG. 2, and the cartridge in FIG. 3 are for illustrative purposes only and form no part of the claimed design.
